UNITED STATES PATENT OFFICE.

LOUIS H. KRICKEL, OF MONROE, LOUISIANA, ASSIGNOR OF SEVEN AND ONE-HALF PER CENT. TO CHARLES SCHULTZE, SEVEN AND ONE-HALF PER CENT. TO RICHARD DOWNS, SEVEN AND ONE-HALF PER CENT. TO HENRY M. HOWELL, SEVEN AND ONE-HALF PER CENT. TO JOHN E. DOUGHTIE, SEVEN AND ONE-HALF PER CENT. TO E. L. OWENS, AND SEVEN AND ONE-HALF PER CENT. TO SHELBY C. BLACKMON, ALL OF MONROE, LOUISIANA.

WHEEL.

1,358,757.

Specification of Letters Patent. Patented Nov. 16, 1920.

Application filed December 10, 1918. Serial No. 343,691

To all whom it may concern:

Be it known that I, LOUIS H. KRICKEL, a citizen of the United States, and a resident of Monroe, in the parish of Ouachita and State of Louisiana, have made certain new and useful Improvements in Wheels, of which the following is a specification.

This invention relates to an improved wheel, and more particularly to a demountable rim therefor.

An important object of the invention is to provide an improvement of this character in which the rim parts are so formed and associated with each other that while they are positively retained assembled and in position for immediate mounting on the wheel when the rim is carried as a spare rim, they are adapted to be easily and readily disassembled and reassembled to remove and replace the tire when necessary.

Another important object is to provide an improvement of this character in which in event of emergency the rim may be removed and the travel necessary to place of relief may be made without danger of distortion or breakage of the exposed structure.

Another object is to provide an improvement of this character of great strength and durability, efficient in practice, easy to operate and inexpensive to manufacture.

Other objects and advantages reside in the certain novel features of the construction, arrangement and combination of parts, and will become apparent as the description proceeds, reference being had to the accompanying drawings forming part of this specification, and in which:—

Figure 1 is a transverse sectional view showing my invention embodied in an ordinary wooden wheel;

Fig. 2 is a transverse sectional view showing my invention embodied in the conventional wire wheel;

Fig. 3 is a fragmentary side elevation;

Fig. 4 is a detailed view in transverse section of the means for locking the outer tire retaining flange to the rim;

Fig. 5 is a similar view showing a modified form of outer locking plate;

Fig. 6 is a detailed view of the locking bolt for the locking plates;

Fig. 7 is a perspective view of the stud bolt nut used on the wooden wheel;

Fig. 8 is a perspective view of the stud bolt nut used on the wire wheel.

Referring to the drawings, especially to Figs. 1 and 3, it will be seen that one embodiment of my invention contemplates an auto wheel including a hub 10, spokes 11 and a felly 12, preferably of wooden construction. A felly band 13 is shrunk or otherwise secured upon the felly 12 and is provided at its inner edge, that is, at the edge adjacent the vehicle, with a vertical upstanding flange 14, and is provided at its outer edge with a bevel 15 constituting an inclined surface. Both the flange 14 and the inclined surface 15 extend entirely around the circumference of the felly band.

The felly is provided with a plurality of transverse openings 16, which communicate at their inner ends with recesses 17 to receive the stud bolts and stud bolt nuts, as will be hereinafter more fully described.

A removable wedge ring 18 is positioned upon the felly band adjacent the upstanding flange 14, and presents an inclined surface 18' as shown.

The demountable rim consists of a base section 19 having an inner integral tire engaging and retaining flange 20, and having formed on its outer side an inner vertically depending locking plate 21, the inner face of which is adapted when the rim is in position to bear against the outer face of the felly. An outer tire engaging and retaining flange 22 has integrally formed therewith a vertically depending outer locking plate 23, the inner face of which is adapted, when the rim parts are assembled, to bear against the outer face of the inner locking plate 21. Both of the locking plates extend entirely around the circumference of the rim. The underside of the base section of the rim is provided with an integral downwardly extending circumferential flange 24, having an inclined face 24' corresponding to the inclined face 18' of the wedge ring 18, and at the outer side the underside of the base section is provided with a wedge ring 25, which may be removable, if preferred, and which is formed with an in-

inclined surface 27' corresponding to the inclined surface 15 of the felly band 13. When in engagement these inclined surfaces coöperate to properly position the rim 5 spaced from the felly band.

The inner locking plate 21 is provided with a plurality of threaded openings 21', shown in Figs. 4 and 5, preferably six in number, to receive the inner threaded portion 26 of the locking bolt. The threaded portion 26 is of slightly less diameter than the smooth portion 27 of the bolt, and when the bolt is threaded into locking position, the shoulder 27' thus formed abuts against 10 the adjacent outer face of the inner locking plate 21. The head 28 of the locking bolt is provided at its inner peripheral edge with a bevel surface 28'. In the outer locking plate 23 there is formed a plurality of enlarged openings 29 of sufficient size to permit passage therethrough of the heads 28 of the locking bolts and communicating with each of these openings is a circumferentially extending slot 30, of slightly greater diameter than the smooth portion 27 of the locking bolt whereby to permit entrance of the smooth portion 27 into the slot, but to prevent passage of the head 28 through the slot. The bevel 28' of the head greatly facilitates, and in fact is the only means by which it is made practically possible to move the locking plate 23 circumferentially, so that the smooth portion 27 of the locking bolt will enter the slot 30.

When the rim is assembled with the tire thereon, and is mounted on the wheel in proper position, it is retained in this position by the action of the stud bolts, 31. These stud bolts 31 are preferably six in 35 number, and extend through suitably aligned openings 32 and 33 formed in the outer and inner locking plates respectively, and through the openings 16 in the felly 12. The end of each of the stud bolts is threaded, as shown at 31', and is adapted to be seated in the threaded bore 34' of the stud bolt nut 35. The stud bolt nuts 35 are each seated in a recess 17 provided therefore in felly 12, and are formed with arcuate 50 wings 36, which in position are coincident with the outer face of the felly, and as the recesses 17 in which each nut 35 is received conforms to the contour of the nut, these wings 36 prevent the nut from turning and 55 render it stationary at all times. A radially extending flange 37 adapted to bear against the inner face of the felly 12 as shown in Fig. 1 is also provided.

As shown in Fig. 5, the outer locking plate 23 of the separable tire retaining and engaging flange 22 may be bent to present concavo-convex cross section or outwardly bowed portion 38. This construction brings the resiliency of the metal constituting the 60 locking plate into play and renders the

plate more particularly adapted to partake of its operative movements. The outwardly bowed portion 38 is formed of course intermediate the bearing portions of the locking plate.

In the form of locking plate shown in Fig. 4, a thin gasket 39 of suitable material and impregnated with paraffin or the like is disposed between the locking plates, but in the form of the locking plate shown in Fig. 5, the gasket is dispensed with.

In Fig. 2, the invention is shown embodied in a wire wheel construction, the numeral 40 designating the spokes of the wheel, and the fixed rim thereof is shown at 41. The fixed rim serves for both the felly and felly band and consists merely of an annular ring, rectangular in cross section and preferably constructed of metal. This fixed rim 41 is provided with an integral upstanding flange 42 corresponding to the flange 14 of the embodiment of my invention shown in Fig. 1, and with an inclined surface 43 also corresponding to the inclined surface 15 of Fig. 1. The outer edge of the fixed rim 41 is provided with a vertically depending integral plate 44 extending entirely around the circumference. This plate 44 is provided with a plurality of openings 45 therethrough which correspond to the openings 16 of Fig. 1, and these openings receive the short stud bolts 46 of this form of my invention. The inner threaded end 46' of these stud bolts coöperates with stud bolt nut 47 shown in detail in Fig. 8. The inclined bevel surface 49 of nut 48 seats in the corner between the fixed rim 41 and the plate 44, and this nut 48 is secured to the fixed rim 41 and plate 44, or is made separable therefrom, as desired.

The demountable rim, its locking plates and associated structure, and the means for properly positioning and spacing the rim from the felly are precisely the same in this embodiment of my invention, as in the embodiment shown in Fig. 1, being shown in detail in Figs. 3, 4, 5 and 6. In both embodiments of my invention, the outer tire engaging and retaining flange 22 is provided with impact lugs 50 which may be operated upon by a hammer or suitable tool to induce the relative movement of the locking plates necessary to move the locking bolt in or out of the slot 30, as desired, so therefore to assemble or disassemble the demountable rim.

A tire 51 is mounted on the base 19 of the rim between the tire engaging flanges 20 and 21, and is held in position by these flanges and the base section.

In practice when it is desired to remove the tire for replacement or repair, the stud bolts 41 or 46, as the case may be, are removed and the entire rim and tire may then be taken from the wheel. The locking bolts may, if desired, be left untouched, and the

rim laid flat on the ground with these bolts on the upper side. The impact lugs 50 are then operated upon by a hammer or other suitable tool in such manner that the outer locking plate will be moved so that the locking bolts will be displaced from the slots 30 into the openings 29, and the outer tire engaging flange 22 with its locking plate 23 may be then withdrawn, the locking bolt 10 passing through the openings 29. In assembling the rim the locking plate 23 of the outer tire engaging flange 22 has its openings 29 alined with the locking bolts, and is then moved toward the rim, so that the locking bolts project through the openings. The impact lugs 50 are then operated upon in such manner that the locking plate 23 is moved circumferentially of the locking plate 22 to cause the locking bolts to enter the 20 slots 30. The bevel 28 of the locking bolts presents an inclined surface to the locking plate 23, and in this manner forces the same inwardly against the locking plate 21, and greatly facilitates if not only makes practically possible, this assembly. In the event of emergency the demountable rim may be entirely removed, as well as the wedge ring 18 and the travel to place of relief may be made upon the felly band 13. This felly 30 band is positively supported and of such cross section and strength that it will not be distorted or damaged by this exposure.

I claim:

1. In a device of the character described,

a demountable rim including a base section 35 having an inner locking plate integral therewith, a separable tire retaining flange having an outer resilient locking plate provided with bearing portions adapted to be disposed against said inner locking plate, and an intermediate outwardly bowed portion spaced from the inner locking plate to be free to partake of flexion when the resiliency of the plate comes into play, and means engaged with said inner locking plate and adapted to 45 be engaged with the outwardly bowed portion of said outer locking plate to secure said inner and outer locking plates together, all as and for the purposes set forth.

2. In a device of the character described, 50 a demountable rim including a base section having an inner locking plate integral therewith, a separable tire retaining flange having an outer resilient locking plate provided with bearing portions adapted to be disposed 55 against said inner locking plate, an intermediate outwardly bowed portion spaced from the inner locking plate to be free to partake of flexion when the resiliency of the plate comes into play, and a locking bolt including a head adapted to be engaged with the outwardly bowed portion and a shank having threaded engagement with the inner locking plate to secure said inner and outer locking plates together, all as and for the 60 purposes set forth.

LOUIS H. KRICKEL.
